(57) **CLAIM**

The ornamental design for a bracket, as shown and described.

DESCRIPTION

FIG. 1 is a top-front perspective view of a first bracket showing the new design;

FIG. 2 is a bottom-rear perspective view of the first bracket;

FIG. 3 is a top view the first bracket;

FIG. 4 is a bottom view the first bracket;

FIG. 5 is a left side view the first bracket, with the right side view being a mirror image of the left side view;

FIG. 6 is a front view the first bracket;

FIG. 7 is a back view the first bracket;

FIG. 8 is a top-front perspective view of a second bracket;

FIG. 9 is a bottom-rear perspective view of the second bracket;

FIG. 10 is a top view of the second bracket;

FIG. 11 is a bottom view of the second bracket;

FIG. 12 is a left side view thereof, with the right side view being a mirror image of the left side of the second bracket;

FIG. 13 is a front view of the second bracket; and,

FIG. 14 is a back view of the second bracket.

The bracket is shown with symbolic breaks along its length in FIGS. 8-14. The appearance of any portion of the article between the break lines forms no part of the claimed design.

1 Claim, 10 Drawing Sheets
